UNITED STATES PATENT OFFICE.

ERNEST RIEMENSCHNEIDER, OF HIGHLAND PARK, MICHIGAN, ASSIGNOR TO FORD MOTOR COMPANY OF DELAWARE, OF DETROIT, MICHIGAN, A CORPORATION OF DELAWARE.

MACHINE AND METHOD FOR ELECTRIC HEATING FOR UPSETTING AND FORMING.

1,359,199.

Specification of Letters Patent. Patented Nov. 16, 1920.

Application filed June 7, 1920. Serial No. 386,957.

To all whom it may concern:

Be it known that I, ERNEST RIEMENSCHNEIDER, a citizen of the United States, residing at Highland Park, in the county of

5 Wayne and State of Michigan, have invented new and useful Improvements in Machines and Methods for Electric Heating for Upsetting and Forming, of which the following is a specification.

10 The object of my invention is to provide an improved machine and method for electric heating for upsetting of simple, durable and inexpensive construction.

15 A further object of my invention is to provide means for heating metallic articles by electricity so that they may be shaped for a particular purpose, such for instance as upsetting one end to form a head.

20 A further object of my invention is to provide means for heating the portion only of the object, which is to be upset or formed, so that the balance of the object may be shaped and finished to a desired dimension prior to the shaping or upsetting thereof.

25 A further object of my invention is to provide means for uniformly heating throughout its length, or substantially uniformly heating, that portion of the object which is to be upset or formed.

30 A further object of my invention is to provide a machine for accomplishing the foregoing object comprising a pair of electrodes one of which is adapted to grasp or inclose the portion of the object which is not

35 to be heated, to provide means for causing it to grasp and release the object, to provide means for bringing the electrodes toward and from each other for the purpose of moving the object into and out of contact

40 with the second electrode, to provide adjustable means on the second electrode for causing a maximum amount of contact between the object and the electrode, and a unitary controlling lever structure adapted to both

45 close the first electrode, bring the electrodes together, and to switch on the current through these electrodes and the object.

With these and other objects in view, my invention consists in the arrangement, combination and construction of the various parts of my improved device, as described in the specification, claimed in my claims,

and shown in the accompanying drawings in which:

Figure 1 is a top or plan view of my improved device. 55

Fig. 2 is a vertical sectional view taken on the line 2—2 of Fig. 1.

Fig. 3 is a front elevation of the device, and 60

Fig. 4 is a vertical, sectional view taken on the line 4—4 of Fig. 3.

Referring to the accompanying drawings I have used the reference numeral 10 to indicate generally the base of my improved 65 device, adjacent to which is supported a transformer 11, which is of ordinary construction and adapted to furnish current of sufficient amperage to furnish the heating necessary for the object which is to be 70 heated. Extended forwardly from the transformer 11 are conductors 12 and 13. In this instance the conductors 12 and 13 are illustrated as being formed from a large number of contiguous copper strips in order 75 that maximum conductivity may be secured in proportion to the size of the conductors. The forward end of the conductor 12 is secured by bolts 14 and a plate 15 to an electrode 16 which is adjustably mounted on one 80 end of the base 10. In this connection it will be understood that either the base 10 or a plate 17 should be composed of insulating material to insulate the electrode 16. 85

The electrode 16 preferably has a countersunk portion or recess 18 adjacent to its upper, inner edge which is adapted to receive a nut 19. The nut 19 is rotatably mounted on a bolt 20 which is extended upwardly from the electrode 16 within the recess 18 90 and may be held from rotation on the bolt by a lock nut 21 and washer 22.

The electrode 16 may, if desired, be adjustably mounted to reciprocate on the base 10 within guide members 23, which are fixed 95 to the base at either side thereof. The electrode may be locked from movement in the guides 23 by tightening the bolts 24 against these guides to thereby tighten them against the plate 17. 100

The forward end of the conductor 13 is secured by bolts 25 and a plate 26 through a vertical flange 27 of a plate 28. Plate 28 is mounted to reciprocate on a line parallel

with the axes of the guides 23 in a groove 29 in the base 10. Guides 30 may be tightened against the plate 28 to either lock it from movement or to take up the wear thereon due to moving of the plate within the recess 29.

Fixed to the upper portion of the flange 27 is an electrode member 32 which has a vertical opening therethrough. An extension 10 33 is projected upwardly and rearwardly from the upright flange 27 and supports a pivot 34 upon which is mounted the rear end of the second section 35 of my second electrode. The member 35 has a recess 36 there-15 in designed to loosely receive a bar 37 or actuating rod which is pivotally mounted on a horizontal axis within the recess 36 at 38.

From the construction of the parts just described it will be seen that reciprocation 20 of the actuating rod 37 will cause a similar movement of the section 35 due to the fact that the rear end of this section is pivoted at 34 to the bracket 35. In this connection it will be noted that this pivotal mounting is 25 allowed sufficient play to compensate for the direction of movement of the rod 37. This rod 37 is loosely received in the member 32 to permit vertical movement. The member 35 is electrically connected to the conductor 30 13 by flexible conducting strips 39 so that movement of the member 35 will not effect the electrical connection of that member with the transformer. Members 40 and 41 are detachably mounted respectively in the 35 lower and upper surfaces of the members 35 and 32 by means of plates 42 which are secured to the members 35 and 32 by bolts 43. The members 40 and 41 have corresponding 40 sockets therein whereby when they are brought together an object may be inclosed within the said sockets. These members are also formed of a different material in certain instances from the material in the members 32 and 35. In this connection it will 45 be noted that the members 35 and 40 and the members 32 and 41 form respective sections of the electrode connected with the conductor 13.

For moving the sections of this electrode 50 to and from each other the following means are provided. A plate 44 is bolted to the base 10 and extends upwardly from the rear edge thereof. A lever 45 has a ball indicated by the dotted lines 46 which is received 55 within a corresponding socket in the plate 43. This lever is connected with the operating rod 37 by a pin 47 to permit slight universal movement. At the forward edge of the base 10 a plate 48 is secured by bolts 60 49 and provided with a slot 50 designed to receive the lever 45. The slot 50 is arranged with its center-line curved upwardly from the left-hand of the slot toward the right-hand end of the slot. If, then, the lever 45 65 be moved from left to right in the slot, it

will be seen that the portion of the lever between the ball 46 and the plate 48 will move from left to right and will also raise somewhat. As this portion of the lever is connected to the actuating rod 37 it will be seen 70 that the actuating rod 37 will also move to the right and upwardly when the lever is similarly moved. Due to the fact that the actuating rod is passed through both sections of the electrodes and to the fact that 75 it is pivotally connected to the upper section as compared with slidably mounted in the lower section, it will be seen that such movement of the actuating rod will move simultaneously both sections of the electrode 80 toward the right and also move the upper section upwardly. It will also be seen that movement of the lever from the upper end of the slot 50 to the lower end will have the effect of simultaneously moving both the 85 electrode members to the left and of closing them together.

Means are mounted on the lever 45 for switching the current on through the electrodes comprising a shell 51 which is connected by a rod 52 to a switch 53 which in turn is connected into the transformer circuit.

In the practice of my invention a clamp 95 may be used to clamp or hold one end of the article which is to be formed and then the electrodes brought to position bearing against opposite sides of the article adjacent to the end thereof to heat the portion only of the article which is between the electrode so that 100 that portion of the article may be, when heated, given a desired form by the means of a die which is either pressed against the heated metal or caused to impact against the heated metal.

In the practical operation of my improved device it will be assumed that it is desired to form an object such as is illustrated at "A" in my drawings with an enlarged head. It will be understood that this device is 110 adapted for heating a portion of an object to do any form of upsetting but that I am here using the example of forming an enlarged head for illustrative purposes only. The electrical current will be connected 115 through the transformer 10 and arranged so that it may be opened or closed by moving the shell 51 on the lever 45. The object "A" is then placed within the recesses in the members 40 and 41 of the section of the electrode whereby the portion of the object which is not to be heated will be wholly received within the electrodes. The lever 45 is then swung from the right-hand end of the slot 50 to the position, or substantially the 120 position, illustrated in Figs. 1 and 3, which will close together the sections of the electrode and cause the sockets therein to tightly receive the adjacent portion of the object "A." Movement of this lever 45 to this 125 130

position also brings the end of the object "A" into contact with the nut 19, but the incline of the slot 50 and position of the electrode 16 should be such that the sections 5 will grip the object before the contact is complete. If then the shell 51 be operated to complete the circuit through the portion of the object "A," which is between the electrode, that portion, and that portion only, 10 of the object will be heated to substantially any desired degree of temperature, dependent upon the strength of the current and the time which it is allowed to flow through the object.

15 In this connection I have made a large number of experiments with the use of my improved device and find that I can readily heat the portion of the object between the electrodes to a cherry red within a very 20 small space of time, then separate the electrodes and remove the object from between the electrodes with the bare hands, if care is taken to grasp the object by the end opposite the heated end. It will be noted that 25 both ends of the object project from the sections of the electrode, so that the unheated end may be grasped by the hand. This result not only facilitates the handling of the objects which are being heated but also 30 enables me to machine and finish a bar, shackle, or the like, and then form thereon the head or other upset portion without affecting the finish of the remaining portion 35 of the object. This is one of the most important advantages resulting from the use 40 of my device as it is relatively easy to machine a long bar before it is cut into pieces and upset, while on the other hand it is both difficult and expensive to machine the portion 45 of an object adjacent to the upset portion thereof.

It has heretofore been noted that the pieces 40 and 41 are separable from the pieces 35 and 32 and that they are in certain instances composed of different material from that of the members 35 and 32. I have found that where there is a comparatively small amount of surface contact between the object and the fixed electrode 16, there is a 50 tendency for the object to fuse at the point of contact with the fixed electrode due to the relatively greater resistance resulting from both the poor contact and small cross-sectional area of conductor. This difficulty 55 may be obviated in my improved device by making the movable members 40 and 41 of such material that the resistance on the side of the split electrode will be substantially equal to the resistance to the point of contact with the fixed electrode. By this construction I have found by repeated experiments that I am able to secure a substantially uniform heating of the object between the two electrodes. It will also be noted 60 that I have so arranged the fixed electrodes

that a maximum contact surface may be obtained between the electrodes and the object by adjusting the nut 19 so that its surface adjacent to the end of the object with which it is brought into contact may be 70 made as nearly as possible parallel with the surface of the end of the object. Adjustment of this nut therefore reduces the resistance at the point of contact to a minimum thereby further insuring more uniform 75 heating of the portion of the object between the electrodes. The advantages resulting from the use of my improved device therefore consist in a large saving in both labor and machinery for machine work and economy in upsetting articles on a production basis.

Some changes may be made in the arrangement and construction of the various parts of my improved device without departing from the spirit of the invention therein and it is my intention to cover by my claims such changes as may be reasonably included within the scope thereof.

I claim as my invention:

1. The method of electrical heating for upsetting, consisting of extending a portion of the object between electrodes, composed of metals having relatively different resistances, whereby the heating of the object 95 may be substantially uniform between the electrodes.

2. The method of electrical heating for upsetting, consisting of placing a portion of the object in one electrode and bringing 100 a portion of the object against another electrode, the first electrode having a conductivity relatively different from that of the second whereby only the portion of the object between the electrodes may be heated, 105 and that portion may be heated substantially uniformly throughout its length.

3. In a device of the class described, a base, a fixed electrode mounted thereon, a movable member on said fixed electrode 110 whereby the surface of said movable member may be adjusted to lay in a plurality of different planes, a split electrode, means for moving the sections of the split electrodes toward and from each other, and 115 means for slidably mounting said split electrodes on the base whereby said electrodes may be moved toward and from each other and a portion of the object grasped between the members of the split electrodes 120 to thereby heat the portion only of the object which is between the electrodes.

4. In a device of the class described, a base, a fixed electrode thereon, a pair of plates mounted respectively on the back and 125 front of the base, a lever mounted for universal movement in one of said plates and extended through a slot in the second plate, said slot being so arranged that the lever moving along said slot will travel both 130

4

horizontally and vertically, an electrode comprising two members slidably mounted on said base adjacent to said lever, and means for operatively connecting said lever with said split electrode members whereby movement of the lever in one direction will move the entire electrode on movement of the lever in a direction perpendicular thereto and will separate and bring together the members of the electrode.

5. In a device of the class described, a base, a pair of electrodes thereon, one of said electrodes being divided into sections, a lever, and means for operatively connecting said electrodes with said lever whereby movement of the lever in one direction may separate both the electrodes and the sections of the divided electrode, and movement of the lever in the opposite direction may bring together the sections of the divided electrode and the electrodes themselves.

6. In a device of the class described, a base, a pair of electrodes mounted thereon, one of said electrodes being divided into sections and a lever, means for operatively connecting said lever with said electrodes whereby movement of said lever in opposite directions may selectively move both the electrodes and the sections of the divided electrode toward and from each other, and means mounted on said lever for opening and closing the circuit through said electrodes.

7. The method of electrical heating for upsetting, consisting of extending an object between electrodes composed of metals having relatively different resistances, whereby

the heating of the object may be substantially uniform between the electrodes.

8. In a device of the class described, a hand electrode movable to permit its faces to lie in a plurality of different planes, a second relatively immovable electrode, and means for moving said electrodes toward and from each other to thereby complete a circuit through an object extended between the electrodes, the parts being so arranged that the movable electrode may be moved so that one of its surfaces may lie in a plane parallel to the plane in which the end of such an object may lie when the electrodes are brought toward each other to complete the circuit.

9. In a device of the class described, a pair of electrodes movable toward and from each other to thereby complete a circuit through the electrodes and an object placed between them, and means for adjusting the position of the contacting face of at least one of said electrodes so that said contacting face may lie in a plane parallel to the contacting portion of the object placed between said electrodes.

10. In a device of the class described, a base, a pair of electrodes mounted thereon, one of said electrodes being divided into sections, a lever, and means for operatively connecting said lever with said electrodes whereby movement of said lever in opposite direction may selectively move both the electrodes and the sections of the divided electrode toward and from each other.

ERNEST RIEMENSCHNEIDER.
